AUTOMATIC ELECTRIC TRAFFIC SIGNAL SYSTEM

Harry G. Hunter, Greensboro, N. C.

Application June 8, 1936, Serial No. 84,194

3 Claims. (Cl. 177—339)

My invention relates to improvements in automatic electric traffic signal systems, and it consists in the combinations, construction, and arrangements herein described and claimed.

5 My invention is particularly designed for use at dangerous intersections of highways, in the country rather than the city streets although it could be used in the city where desirable.

An object of the invention is to provide a 10 signal system, the use of which will speed up traffic without danger since it does not depend upon clock mechanisms which often cause unnecessary delays, but which is operated in accordance with the traffic demands automatically.

15 A further object of the invention is to provide a system of the type described in which the protected intersection is open for traffic upon one of the intersecting highways at all times, unless a vehicle upon the other of said highways shall 20 have energized a signal to be displayed which would then cause traffic upon the first named highway to stop until the vehicle which actuated the signal cleared the crossing.

A further object of the invention is to provide 25 a traffic signal system in which the signal lights, automatically controlled by the vehicles approaching the intersection upon one highway, will remain on for a predetermined period and will then be restored to normal condition.

30 A further object is to provide a signal system in which, if a number of vehicles are approaching the intersection upon one highway, the signals operated by the first one will be maintained by the succeeding vehicles, and in which 35 the signal lights are only restored to normal when the last vehicle has cleared the intersection.

Other objects and advantages will appear in 40 the following specification and the novel features of the invention will be particularly pointed out in the appended claims.

45 My invention is illustrated in the accompanying drawings forming part of this application, in which:

Figure 1 is a diagrammatic view partly in perspective showing the intersecting highways and the location of the signal lights and the switches which control them.

50 Figures 2, 3, 4 and 5 are illustrations of the appearance of the lights under varying conditions, and

Figure 6 is a diagrammatic view of the circuits for operating the signal lights.

Figure 7 is an across-the-line diagram of Fig. 6.

55 Referring now to Figure 1, I have shown there- in intersecting highways which I have indicated

as "Superior highway" and "Inferior highway" with a signalling device S preferably suspended from poles p. In the form illustrated, the lights of the signal S are controlled solely by the passage of vehicles along the Superior highway. It 5 will be noted that at a predetermined distance from the intersection are the switches A and B for vehicles approaching from the left of Figure 1. Similar switches A' and B' are for vehicles approaching from the right in Figure 1. These 10 switches are set far enough from the intersection to permit a vehicle traveling upon the Inferior highway at a maximum rate of speed to stop before reaching the intersection after the actuating vehicle upon the Superior highway has 15 crossed switch B (or B'), thus causing the operation of the lights. The distance between the switches A and B and A' and B' is determined by the time interval desired after the vehicle passes A and before it passes B (similarly for A' 20 and B'). These pairs of switches function as a directional switch and may be combined in a single switch of special design.

In Figure 6 I have shown the circuits which are actuated by the closure of the switches A and B 25 at the left of the drawing and by the switches A' and B' at the right of the drawing and in the central portion of the figure I have shown the circuits leading to the lights and the devices for controlling the same.

It will be observed that in the mechanism controlled by switches A and B I have provided a relay R, a time switch mechanism T, a multiple contact switch M and a second switch V. Similar mechanism is indicated at the right hand 35 side of the drawing at R', T', M' and V', respectively.

For the controlling of the lights I use a time limit relay G which will open a circuit after the lapse of a relatively long period of time following the beginning of the passage of current through the relay. This interval may be fifteen seconds. A similar switch is shown at K. F is a multiple contact switch and H is a similar switch. P indicates a delayed closing relay which closes 45 a circuit after delay of a relatively short period, say, one to two seconds, after current shall have begun to pass through the relay. O and W are electric contact switches and X, Y and Z indicate electric lamps.

In the drawings I have shown the Inferior highway as being open to traffic unless the signals are set by traffic along the Superior highway but it will be understood that either highway might control the signals for the other. The 55

normal position of the apparatus is that shown in Figure 6. In this figure current from the source of power I passes through 2 to Z, contacts 3, 4, 5, 6 and by conductors 7 and 8 to line wire II. This energizes the red or "danger" light Z for the Superior highway and the green or "clear" light for the Inferior highway.

Now let us assume that a vehicle approaches on the Superior highway from the left. The 10 switch A is traversed and the closure of the switch A sets up two circuits as follows:

(1). From the main line I through A, 9, coil of relay R, 10, coil of switch M, 11 and by 12 to power source II.

(2). From power source I, A, 9, R, 13, T, 14, 11, 12 to II.

Three results follow:

(a) The contacts of the relay R are closed and locking circuits are set up from line I through 15, 16, 17, 18, 19, 20, R and by the paths already traced through the timing relay T and the coil of switch M, 11 and 12 to line II.

(b) The starting of the timing element of T, which is adjusted to open the locking circuits at 25 18 and 19 after a period of time determined by the time required for a vehicle traveling at a minimum predetermined speed to pass over the switch B.

(c) The closure of the contacts of the switch 30 M at 21—22, 23—24, and 25—26, but these closures do not set up circuits because of openings in these circuits at other points as will be described.

The vehicle next closes the switch B. This 35 results in setting up of a circuit from the line I through 27, B, 28, 21, 22, 29, coil of switch V and back to line II by conductor 12. The action of the switch V causes a circuit from line I, through 30, 23, 24, 31, 32, 33, coil of switch F, 34, 35, 36, coil of time limit switch G, 37, 38, 39, 40, 26, 25 to line II. This circuit results in the

(a) Starting of the time mechanism of the switch G and

(b) Closes the switch contacts of the switch F. The latter action

(1) Sets up a locking circuit from the line I through 41, 42, 43, 44, coil of delayed closing relay F, 45, coil of switch F, 34, 35, 36, coil of timing relay G, 30, 47, 48, 49, 50, 8 to II. The relay P is energized and it closes its contacts after a predetermined interval. The purpose of this relationship is to prevent the closing of the switch H and the time limit switch K, simultaneously with F and G, but to permit the closing of H and K if a second actuation of the switches A and B shall have been had prior to the restoration of the system to normal through the operation of time switch mechanism G in opening contacts 35 and 36.

(2) Sets up the signal circuit from the line I through 41, 42, 43, 46, signal lamp X, 47, 48, 49, 50, and by 8 to line II.

(3) Sets up a circuit from line I through 41, 42, 43, 46, 51, coil of switch O, 52, and to line II by the circuits already traced. When the switch O is actuated the contacts 3 and 4 are opened thus extinguishing the lamp Z.

(4) After the lapse of a selected period the delayed closing relay P closes its contacts by means of which H and K will function if the switches A and B are again operated before F and G are restored to normal. This operation will be explained later.

At the expiration of the predetermined period 75 of time for which it is adjusted (this time being

determined by the time required for a vehicle traveling at a selected rate of speed to travel from the switch B through the intersection), the time switch mechanism G opens the circuit at the contacts 35, 36, through the switch F which thereupon opens its contacts 43—42 and 48—49, thus causing the system to return to normal.

For a second vehicle approaching upon the Superior highway either following the first vehicle or traveling in the opposing lane and in the opposite direction so that the second vehicle operates switches A and B or A' and B' before the switch G shall have operated to restore the system to normal after the passage of the first vehicle, the following sequence occurs:

1. The system is in the actuated condition as described in paragraphs (1) to (4), inclusive, above.

2. The second vehicle causes switch A to operate and perform the same functions described heretofore.

3. The second vehicle causes the corresponding switch B to operate instantaneously which sets up the same circuits as described previously but causes none of the devices in those circuits except switch V to operate because they are already energized and function as a result of the initial operation and in addition sets up the instantaneous circuit from line I, through 30, 23, 24, 31, 32, 33, 45, 53, 54, 55, 56, coil of switch H, 57, 58, 59, 60, coil of relay K, 61, 38, 39, 40, 26, 25 and by 62 to line II.

This results in the:

(a) Starting of the time mechanism of the relay K.

(b) Closes the switch H which

(1) Sets up a locking circuit from line I through 2, 63, 64, 65, 66, coil of switch H, 57, 58, 59, 60, coil of relay K, 61, 68, 69, 70, 82, 7 and 8 to line II.

(2) Sets up the signal circuit from line I through 2, 63, 64, 65, 67, signal lamp Y, 68, 69, 70, 82, 7, 8, to line II, thereby operating the signal Y.

(3) Sets up a circuit from line I, through 2, 63, 64, 65, 67, 72, coil of switch W, 73, and by 68 and the circuit previously traced to line II. When the switch W operates the circuit is broken at 5 and 6 so as to prevent the light Z from operating until the system is returned to normal.

At the expiration of a predetermined period of time for which it is adjusted (being determined by the time required for a vehicle travelling a selected rate of speed to travel from B through the intersection) the time switch mechanism K opens the circuit from the line I at the contacts 58 and 59, thereby de-energizing the circuit through H and causing the system to return to normal.

In the event that a third vehicle should approach the system before the signal returns to normal, after its operation by the second vehicle but after the switch G shall have operated as a result of the passage of the first vehicle, the system operates as heretofore described for the first vehicle.

It will be seen that this system will permit vehicles on the Superior highway to pass in succession and to maintain a green light for "clear" passage while a red light will be maintained for the Inferior highway and after the traffic has cleared on the Superior highway then the various instrumentalities will be restored to normal so that the traffic on the Inferior highway may pass. When there is no traffic on the Superior highway the green light or "clear" passage will be displayed.

The system will not be operated by vehicles travelling away from the intersection. Should such vehicles travel so far into the lane or lanes habitually used by opposing traffic as to pass over 5 the switches A and B, these switches will be closed but in the reverse order for operation. Since no means is provided to hold B closed until A is closed, it will immediately open and prevent the setting up of operating circuits. The switch A 10 will remain closed for the time determined by the time limit relay T but this time is so short that the switch will be returned to its normal condition before an approaching vehicle can reach it, as the vehicle which is travelling on the wrong 15 side of the road will require more time to clear the traffic lane for the approaching vehicle than is required to release the circuits through the switches controlled by the relay T.

In Figure 1, as stated, I have shown two circuits 20 which are actuated by switches on the runway, i. e., the switches A—B and A'—B'. It will be apparent from an inspection of the drawings that a vehicle approaching from the right of Figure 1 will operate the switches precisely in the same 25 manner as that already described as approaching from the left so that a description of the operation of one of the circuits will suffice for both.

In Figs. 2 to 5, inclusive, I have shown the various conditions that exist. Figure 2 shows the normal condition with the "danger" signal Z showing on the Superior highway and the "clear" signal Z' showing on the Inferior highway. Both signals are displayed by energizing a single lamp which 30 shows to the respective highways through properly placed colored lenses. In Figure 3 the condition is shown where there is one vehicle in the block on the Superior highway. At this time the light X, which indicates "clear" is shown on the Superior highway and the "danger" light X' on 35 the Inferior highway. These signals are displayed by a single lamp as above described in connection with signals Z and Z'.

In Figure 4 is shown the condition where there are two vehicles in the block. Here the "clear" 40 lights X and Y are shown on the Superior highway while the two "danger" signals X' and Y' are shown on the Inferior highway.

In Figure 5 the condition is indicated where the second vehicle is in the block on the Superior 45 highway when the first vehicle has cleared and in this instance the "clear" signal Y is shown on the Superior highway and the "danger" signal Y' on the Inferior highway.

It will thus be seen that I have provided a system which is automatic and in which the delays 50 occasioned by the holding up of traffic, for instance, on a highway in the country where there are no vehicles even in sight on the intersecting highway, are obviated since, as stated, it is the presence of vehicles on one highway that controls the lights for a predetermined interval of time. After the lapse of an interval of time sufficient for these vehicles to have passed the intersection the system is restored to normal.

65 I claim:

1. An automatic electric traffic signal system for highway intersections comprising a "danger" signal light normally displayed for one highway, a "danger" signal light adapted to be displayed at times for the other highway, a "clear" signal light normally displayed for the intersecting highway, a pair of "clear" signal lights adapted to be

automatically displayed at times for the first-mentioned highway, a pair of roadway switches on one highway on each side of the intersection, the switches of each pair being spaced apart and being at a definite distance from the intersection, 5 means actuated by the conjoint action of that pair of switches on the side of the intersection by approaching traffic for changing the "danger" signal light to "clear" and the "clear" signal light to "danger" and including means which is adapted to be set in motion by a second vehicle passing over one of the pairs of switches nearest the intersection for maintaining the "danger" signal for the second highway in operation while causing the second "clear" signal for the first-mentioned 10 highway to be displayed, the means actuated by the conjoint action of the pair of switches also including means for delaying the cutting off of the "clear" signal light after both pairs of switches have been operated. 20

2. An automatic electric traffic signal system for highway intersections comprising a "danger" signal light normally displayed for one highway, a "danger" signal light adapted to be displayed at times for the other highway, a "clear" signal light normally displayed for the intersecting highway, a pair of "clear" signal lights adapted to be automatically displayed at times for the first-mentioned highway, a pair of roadway switches on one highway on each side of the intersection, 30 the switches of each pair being spaced apart and being at a definite distance from the intersection, means actuated by the conjoint action of that pair of switches on the side of the intersection by approaching traffic for changing the "danger" signal light to "clear" and the "clear" signal light to "danger", and including means which is adapted to be set in motion by a second vehicle passing over one of the pairs of switches nearest the intersection for maintaining the "danger" signal for the second highway in operation while causing the second "clear" signal for the first-mentioned 35 highway to be displayed, said switch-controlled means including timing mechanism for restoring the signals to their normal condition after a pre-determined interval of time. 40

3. An automatic electric traffic signal system for highway intersections comprising a "danger" signal light normally displayed for one highway, a second "danger" signal light adapted to be displayed at times for the other highway, a "clear" signal light normally displayed for the intersecting highway, a pair of "clear" signal lights adapted to be displayed automatically for the first-mentioned highway, a pair of roadway switches 50 on one highway on each side of the intersection, the switches of each pair being spaced apart and being at a definite distance from the intersection, said switches being actuated in a definite sequence by vehicles, means successively actuated by the 55 conjoint action of the switches in proper sequence on the side of the intersection by approaching traffic for changing the "danger" signal light to "clear" and "clear" signal light to "danger", and including means which is adapted to be set in motion by a second vehicle passing over one of the pairs of switches nearest the intersection for maintaining the "danger" signal for the second highway in operation while causing the second "clear" signal for the first-mentioned 60 highway to be displayed. 65

HARRY G. HUNTER.
